UNITED STATES PATENT OFFICE.

CHARLES F. MEYER, OF BRIDGEPORT, CONNECTICUT.

SPARK-PLUG.

1,344,954.

Specification of Letters Patent. Patented June 29, 1920.

Application filed January 23, 1919. Serial No. 273,636.

To all whom it may concern:

Be it known that I, CHARLES F. MEYER, a citizen of the United States, and resident of Bridgeport, in the county of Fairfield and State of Connecticut, have invented certain new and useful Improvements in Spark-Plugs, of which the following is a specification.

This invention relates to improvements in spark plugs or igniters for explosive engines and has for its object to improve upon that class of spark plug shown in my prior patent of September 1, 1914, #1,109,004.

The particular improvement or feature of advantage in my present device over my former patent resides in the special self-adjusting means for connecting the two central metal conductor rods, which enables the parts to be readily assembled and the top cap member of the plug to be screwed on without any liability of cracking the porcelains.

Similar characters of reference will be found to denote similar or corresponding parts throughout the several figures of the accompanying drawings forming a part of this specification, and upon which—

Figure 1 shows a central vertical sectional view through my improved spark plug completed,

Fig. 2 is a side elevation of the plug shown in Fig. 1,

Fig. 3 is a detached view of the two conductor rods shown positioned and connected in Fig. 1,

Fig. 4 is a plan view of the blank from which the telescopic spring socket is formed, shown in Figs. 3 and 5, and

Fig. 5 is a bottom end view of the spring socket as seen from the lower end of the rod 20.

Referring in detail to the characters of reference marked upon the drawings, 8 indicates the metal casing of the plug and 9 the closure cap which is threadably attached to the upper threaded end portion 10 of the casing and which serves to retain the several internal parts of the plug in position. The lower peripheral portion 11 of the plug is also threaded in the usual way to permit of its attachment in the threaded hole of an engine cylinder.

The central chamber 12 within the casing serves to receive the large end portion 13 of the upper porcelain 14 and the annular enlargement 15 of the lower porcelain

16. The lower end of the upper porcelain is seated upon the top side of the enlarged portion 15 of the lower porcelain so as to better retain the parts in a fixed position. The lower porcelain member 15 is provided with a central hole in which the conducting rod 17 is seated. The extreme lower end of this rod projects out from the lower end of the plug to form the sparking end that acts in conjunction with the end 18 extended from the lower end of the casing. This rod is provided with an elongated head 22 as shown, the sides of which are engaged by the yieldable spring jaws 19 secured to the lower end of the upper rod 20 that extends through the porcelain 14 and to the upper end of which the binding nut 21 is threadably attached.

The special construction of the yieldable jaws 19 and the head with which it engages serves to permit the two rod members to be adjusted and telescopically connected and to form a reliable electrical connection between the two, which will not permit the force exerted in securing the cap to the case to be imparted to the rod and porcelain in a manner to crack the same as is liable to happen with the construction in my prior patent and other spark plugs of kindred sort.

Having thus described my invention, what I claim and desire to secure by Letters Patent, is:

A spark plug consisting of a casing which is threaded for attachment to a motor cylinder and having extended sparking points, a removable closure cap upon the top end of the casing, two porcelain members within the casing and inclosed by the said cap and having aligned central holes therethrough, two aligned conducting rods one arranged in the hole of each porcelain, one of said rods being provided with a head and the other with a pair of yieldable jaws to telescopically engage the opposite sides of the head to form a self-adjusting telescopic electrical connection for the adjacent ends of the conducting rods.

Signed at Bridgeport in the county of Fairfield and State of Connecticut this 23rd day of January, A. D. 1919.

CHARLES F. MEYER.
